(57) **CLAIM**

The ornamental design for a ledged takedown lever for a pistol, as shown and described.

DESCRIPTION

FIG. 1 is a top, front, left-side perspective view of a first embodiment of a ledged takedown lever for a pistol of my new design;

FIG. 2 is a top, front, right-side perspective view of the ledged takedown lever for a pistol shown in FIG. 1; FIG. 3 is a top, rear, left-side perspective view of the ledged takedown lever for a pistol shown in FIG. 1; FIG. 4 is a top, rear, right-side perspective view of the ledged takedown lever for a pistol shown in FIG. 1; FIG. 5 is a bottom, front, left-side perspective view of the ledged takedown lever for a pistol shown in FIG. 1; FIG. 6 is a bottom, front, right-side perspective view of the ledged takedown lever for a pistol shown in FIG. 1; FIG. 7 is a bottom, rear, left-side perspective view of the ledged takedown lever for a pistol shown in FIG. 1; FIG. 8 is a bottom, rear, right-side perspective view of the ledged takedown lever for a pistol shown in FIG. 1; FIG. 9 is a top plan view of the ledged takedown lever for a pistol shown in FIG. 1; FIG. 10 is a bottom plan view of the ledged takedown lever for a pistol shown in FIG. 1; FIG. 11 is a front elevational view of the ledged takedown lever for a pistol shown in FIG. 1; FIG. 12 is a rear elevational view of the ledged takedown lever for a pistol shown in FIG. 1; FIG. 13 is a right-side elevational view of the ledged takedown lever for a pistol shown in FIG. 1; FIG. 14 is a left-side side elevational view of the ledged takedown lever for a pistol shown in FIG. 1; FIG. 15 is a front, bottom, right-side perspective view of a portion of the ledged takedown lever for a pistol shown in FIG. 1 in a pistol environment; FIG. 16 is top, front, left-side perspective view of a second embodiment of a ledged takedown lever for a pistol of my new design; FIG. 17 is a top, front, right-side perspective view of the ledged takedown lever for a pistol shown in FIG. 16; FIG. 18 is a top, rear, left-side perspective view of the ledged takedown lever for a pistol shown in FIG. 16; FIG. 19 is a top, rear, right-side perspective view of the ledged takedown lever for a pistol shown in FIG. 16; FIG. 20 is a bottom, front, left-side perspective view of the ledged takedown lever for a pistol shown in FIG. 16; FIG. 21 is a bottom, front, right-side perspective view of the ledged takedown lever for a pistol shown in FIG. 16; FIG. 22 is a bottom, rear, left -side perspective its of the ledged takedown lever for a pistol shown in FIG. 16;

(Continued)

FIG. 23 is a bottom, rear, right-side perspective view of the ledged takedown lever for a pistol shown in FIG. 16;
FIG. 24 is a top plan view of the ledged takedown lever for a pistol shown in FIG. 16;
FIG. 25 is a 1 bottom plat view of the ledged takedown lever for a pistol shown in FIG. 16;
FIG. 26 is a front elevational view of the ledged takedown lever for a pistol shown in FIG. 16;
FIG. 27 is a rear elevational view of the ledged takedown lever for a pistol shown in FIG. 16;
FIG. 28 is a right-side elevational view of the ledged takedown lever for a pistol shown in FIG. 16;
FIG. 29 is a left-side elevational view of the ledged takedown lever for a pistol shown in FIG. 16; and,
FIG. 30 is a front, bottom, right-side perspective view of a portion of the ledged takedown lever for a pistol shown in FIG. 16 in a pistol environment.
The broken lines in the drawings disclose unclaimed subject matter only and form no part of the claimed design.
